(57) **CLAIM**

The ornamental design for the chair, as shown and described.

DESCRIPTION

FIG. 1 is a front perspective view of the chair.

FIG. 2 is a back perspective view of the chair.

FIG. 3 is a right side view of the chair.

FIG. 4 is a front view of the chair.

FIG. 5 is a left side view of the chair.

FIG. 6 is a back view of the chair.

FIG. 7 is a top view of the chair.

FIG. 8 is a bottom view of the chair.

FIG. 9 is a front perspective view of the chair in a second embodiment.

FIG. 10 is a back perspective view of the chair in a second embodiment.

FIG. 11 is a right side view of the chair in a second embodiment.

FIG. 12 is a front view of the chair in a second embodiment.

FIG. 13 is a left view of the chair in a second embodiment.

FIG. 14 is a back view of the chair in a second embodiment.

FIG. 15 is a top view of the chair in a second embodiment.

FIG. 16 is a bottom view of the chair in a second embodiment.

FIG. 17 is a front perspective view of the chair in a third embodiment.

FIG. 18 is a bottom perspective view of the chair in a third embodiment.

FIG. 19 is a right side view of the chair in a third embodiment.

FIG. 20 is a front view of the chair in a third embodiment.

FIG. 21 is a left view of the chair in a third embodiment.

FIG. 22 is a back view of the chair in a third embodiment.

FIG. 23 is a top view of the chair in a third embodiment.

FIG. 24 is a left view of the chair in a third embodiment.

FIG. 25 is a front perspective view of the chair in a fourth embodiment.

FIG. 26 is a bottom perspective view of the chair in a fourth embodiment.

FIG. 27 is a right side view of the chair in a fourth embodiment.

FIG. 28 is a front view of the chair in a fourth embodiment.

FIG. 29 is a left side view of the chair in a fourth embodiment.

FIG. 30 is a back view of the chair in a fourth embodiment.

FIG. 31 is a top view of the chair in a fourth embodiment.

FIG. 32 is a bottom view of the chair in a fourth embodiment.

FIG. 33 is a front perspective view of the chair in a fifth embodiment.

FIG. 34 is a back perspective view of the chair in a fifth embodiment.

(Continued)

FIG. 35 is a right side view of the chair in a fifth embodiment.

(56)

FIG. 36 is a front view of the chair in a fifth embodiment.

FIG. 37 is a left side view of the chair in a fifth embodiment.

FIG. 38 is a back view of the chair in a fifth embodiment.

FIG. 39 is a top view of the chair in a fifth embodiment; and,

FIG. 40 is a bottom view of the chair in a fifth embodiment.

The portions in dashed lines do not form part of the design.

1 Claim, 24 Drawing Sheets
